Dempster Mill Manufacturing Co., Beatrice,
Nebr., a corporation of Nebraska

Application December 11, 1930, Serial No. 501,610

13 Claims.

(Cl. 184—4)

This invention relates to a means for preventing the accumulation of moisture within an enclosure and has special reference to a means for use in connection with an enclosure for automatically lubricated mechanisms for preventing an accumulation of moisture therein to emulsify with the oil.

More particularly, this invention relates to a ventilating means so constructed and arranged on a casing for enclosing an automatically lubricated mechanism as to maintain the pressure and temperature on the inside thereof substantially uniform with that of the outside atmosphere and to a means so arranged within the casing as to collect any condensate on the walls thereof and direct the same outwardly therefrom.

Several types of automatically lubricated mechanisms wherein this device would prove a material benefit include pumping jacks, working heads, automatic water systems, windmills or any other mechanism which it is necessary to operate out in the open and perhaps a distance removed from direct supervision by an operator. For purpose of illustration only we have chosen a windmill. In this case the windmill is mounted as to be inconvenient to service. Wherein a windmill is used the location of the ventilating device must be taken into consideration as will be explained later. The windmill chosen for illustration happens to be of the open-top housing type in which the enclosure is completed by a hood or cover of the conventional design. The principles of this invention are just as readily applicable to an enclosure of the integral cast type wherein the enclosure is practically complete within itself.

Mechanisms of this kind are subjected to most severe pressure and temperature changes thereby causing moisture to collect in the interior of the enclosure and in a normal mechanism to enter the oil and cause premature deterioration of the lubricant. It is possible to prevent the formation of certain of these forms of water under certain conditions and it is further possible to divert moisture so that it will not enter the oil. This, of course, is desirable and is the end to which this invention is directed.

It is one of the objects of this invention to provide an apparatus for ventilating an enclosure for automatically lubricated mechanisms of the character indicated above to prevent the accumulation of moisture therein.

Also, it is an object of this invention to provide an apparatus for diverting the moisture from the oil in an enclosure for automatically lubri-

cated mechanisms of the kind to which we above refer to prevent the accumulation of moisture therein.

Another object of this invention is to provide an insulating material so arranged in an enclosure of the type hereinbefore referred to as will prevent the condensation of moisture on that part of the casing to which it is attached.

Other objects and advantages will be herein-after more particularly pointed out and for a more complete understanding of the characteristic features of this invention reference may be had to the following description when taken together with the accompanying drawings, in which latter:

Figure 1 is a top plan view of the device incorporating the features of this invention;

Fig. 2 is a side elevational view with a portion thereof broken away of Figure 1;

Fig. 3 is a vertical sectional view taken on the line 3—3 of Figure 1;

Fig. 4 is a plan sectional view taken on the line 4—4 of Fig. 3;

Fig. 5 is a plan sectional view taken on the line 5—5 of Fig. 2, showing the attachment of the ventilator means to the cover;

Fig. 6 is an end elevational view of a fragmentary portion of the upper end of the cover shown in Fig. 2, illustrating another type of ventilator means; and

Fig. 7 is a fragmentary plan view of the upper portion of the cover showing still another form of ventilator means.

Referring now more particularly to the construction illustrated in Figs. 1 to 5, inclusive, this invention has been illustrated in connection with the operating mechanism for a windmill and includes the open-top housing 10 and a cover 11 for enclosing the open top. These members enclose the automatically lubricated operating mechanism for a windmill, although, of course, it is to be understood that the adaptation of this invention to that specific use is for illustrative purposes only and it will be well within the scope of one skilled in the art to accommodate its use to any automatically lubricated mechanism wherein it is desirable to prevent the accumulation of moisture within the enclosure for the mechanism and thereby to prevent the premature deterioration of the lubricant.

The housing 10 is so designed as to provide a reservoir for containing a substantial supply of lubricant, which lubricant is conveyed to the various parts of the operating mechanism, briefly described hereinafter. A tubular extension 12

extends from one side of the housing and is preferably integrally formed therewith for supporting a wind wheel shaft 13 upon which latter the wind wheel is mounted. Where a vane is employed, 5 the housing is provided with bearing members 14 upon which the vane is movably mounted.

In the particular embodiment shown, the mechanism within the housing comprises a pair of pinions 15 and 16 fixedly mounted on the wind 10 wheel shaft 13 and is engaged by gears 17 and 18, respectively, which latter are rotatably supported on a stud shaft 19. The trunnion 19 is, in turn, rigidly mounted on a suitable bracket 20, which latter may be preferably cast integrally with the 15 housing 10, the gears 17 and 18 being connected by means of pitmans 21 and 22, respectively, to a cross head 23, one end of each of the pitmans being pivotally supported on a pin 24 extending through the cross head. The cross head 23 vertically reciprocates upon a pair of guide rods 25 and 26, both rods being threaded into the main frame 10 and connected at their upper ends by a spacing bracket 27, which latter bracket serves as a means by which the cover 11 is fastened to 20 the housing 10. The main purpose of the cover 11, of course, is to keep out the rain and dirt from the mechanism in the housing 10 and to prevent loss of the lubricant from the housing and it is the purpose of this invention to prevent the condensation of atmosphere within the enclosure provided by the housing 10 and cover 11 due to the 25 changing temperatures and pressures which form water or water vapor or such phenomena as are commonly known as sweating or frosting. The 30 cover 11 is shown as being of a substantial height to enclose mechanisms extending a distance above the housing, although in many instances this cover is merely a substantially flat cap as where the mechanism is included in its entirety in the 35 housing.

In order to maintain the pressure and temperature on the inside of the cover and housing substantially uniform with that of the outside atmosphere, a ventilating means is employed such 40 as is shown more particularly in Fig. 5 of the drawings, the means preferably comprising a tube 28 having the outer walls and inner walls of a substantially Venturi-shape, that is, having a reduced intermediate diametrical portion between 45 enlarged end portions. A pair of ears are formed on opposite sides of the tube for receiving securing means 29 such as rivets or nuts and bolts. It is preferable to dispose the tube or vent 28 on one 50 of the corners of the cover 11, as shown in full lines in Figure 1 when the windmill is of the type controlled by a vane. However, when it is of the type known as the vaneless-type the ventilating means will be disposed on the side of the cover toward the wind wheel as indicated by the position 55 of the vent 28a in dotted lines in Figure 1.

In the operation of a windmill the housing 10 in which the mechanism and wind wheel are mounted is movable with respect to a tubular stem 30 on which it is mounted. The direction 60 of the air current controls the position of the housing with respect to its movement on the tubular supporting stem 30. If a vane is employed it is normally held in the position shown at "A". Automatic regulation provides movement of the 65 vane about its pivot throughout the arc as shown to prevent damage to the mill by high winds. By use of the pull-out mechanism as illustrated at 70 30a the vane may be swung completely through the arc as shown until it reaches the position 75 "B" in which position the mill is pulled entirely

out of the wind. When the vane is in the position "A", the wind wheel is in the wind and the direction of the air current is indicated by the arrow "X" in Figure 1. When the wind wheel is pulled out of the wind as by means of pulling the vane from its position "A" to its position "B", the direction of the air current with respect to the housing is indicated by the arrow "Y". In both positions of operativeness and inoperativeness the vent 28 is so arranged on the cover preferably at 10 the upper end thereof as to present the opening thereof in substantially the direction of the travel of the wind in all the positions of movement of the housing 10 so that the air currents always blow in the direction of the extension of the tube 15 away from the housing instead of directly into the opening of the vent. By reason of the air currents passing the vent in this manner, and particularly where the vent is of a Venturi-shape, the air is deflected from its usual path and we have 20 found produces a partial vacuum at the mouth of the tube which insures a maximum effective ventilation within the enclosure, air, of course, finding its way into the cover through openings at the 25 bottom of the enclosure as shown by the projection of the tube 30 through which the pump rod operates.

When the vaneless-type mill is employed, the air current passes in the direction across the cover in the direction of the arrow "Z" before 30 reaching the wind wheel, the wind wheel being drawn into and out of the wind by reason of the actuation of the elements of the wind wheel, as is well known in the art. In this instance, the vent 28a is provided on the side of the cover 11 facing 35 the wind wheel so that the vent will not face into the wind but the wind will pass by it to produce the effect of a vacuum drawing air from the inside of the cover as in the former illustration.

By thus ventilating the enclosure 11, the temperature and pressure within the enclosure is 40 maintained substantially uniform with the outside temperatures and pressures and changes in temperature and pressure will be recorded within the enclosure at substantially the same time 45 as they are recorded without the enclosure. Condensation of atmosphere is therefore substantially avoided and the oil is maintained in its useful state and not deteriorated by reason of the emulsification therewith of moisture were 50 this ventilation not accomplished.

Referring now more particularly to Fig. 6 of the drawings, a vent 31 is provided in the same relation with respect to the cover at the upper end thereof at one corner when a type of windmill employing a vane is used and on one side of the cover when the vaneless-type of a windmill is used. This ventilator is formed substantially as shown to exclude the possibility of rain being driven into the enclosure. In Fig. 7 another type 60 of tube is employed which may be desirable in other instances of use, the tube being brought more directly out of the top of the housing and having its mouth carried to a far corner where it will receive favorable air currents in all 65 instances of use with respect to the rotatability of the housing on its tubular support.

Referring now more particularly to Fig. 3 of the drawings, a trough 32 has been shown for draining any moisture which might collect on the 70 inside of the cover to the outside of the enclosure. This apparatus may be employed in association with the ventilator 28 or may be used in lieu thereof to divert the condensation from the inside of the enclosure outwardly therefrom. The 75

trough 32 is formed preferably of a piece of sheet material having a vertically extending portion in a spaced relation with the wall of the cover and having a lower portion offset therefrom and secured by any of the usual securing means such as rivets or by welding to the lower end of the cover. The trough is preferably set at an angle with respect to the horizontal in order that but a single outlet 33 be employed for draining the condensate. It is to be understood that the trough may be employed as a precautionary means in addition to the ventilator or as a means in itself for preventing an accumulation of moisture within the enclosure to emulsify with the oil, its use being to divert the moisture from the enclosure rather than to prevent the formation of the moisture.

In connection with the use of the trough 32 it may be desirable to provide an insulating material 34 for the upper end of the enclosure. Wherein the shape of the top of the enclosure is such as may preclude ready draining of moisture to the sides of the enclosure or where for any other purpose it is deemed desirable to insulate part of the enclosure it may be accomplished as illustrated, wherein the insulating material 34 is held against the top of the hood 11 by means of a thin plate 35 of light springy material.

As a result of this invention a method is provided for preventing the accumulation of moisture within the enclosure for automatically lubricated mechanisms including such water or water vapor or such phenomena as are commonly known as sweating, frosting and other forms of water vapor. By the ventilating means it is possible to maintain pressures and temperatures on the inside of the enclosure substantially uniform with those of the outside atmosphere. An apparatus is also provided for frost-proofing certain parts if desired. Also means are shown for the actual physical accumulation and draining off of moisture from within the enclosure. Any one or more of these means may be used singly or in combination to accomplish the desired results.

While several embodiments of this invention are herein shown and described, it is to be understood that various modifications thereof may be apparent to those skilled in the art without departing from the spirit and scope of this invention and, therefore, the same is only to be limited by the scope of the prior art and the appended claims.

We claim:

1. A windmill construction comprising an enclosed oil reservoir mounted to swing about a substantially vertical axis in accordance with the direction of the wind, and means for preventing the accumulation of moisture in said reservoir comprising an air outlet passage carried by said swinging reservoir and having its orifice facing toward the lee side of the reservoir.

2. A windmill construction comprising an enclosed oil reservoir mounted to swing about a substantially vertical axis in accordance with the direction of the wind, and means for preventing the accumulation of moisture in said reservoir comprising an air outlet passage carried by said swinging reservoir and leading from the lee side thereof and having its orifice facing toward the lee side of the reservoir.

3. A windmill construction comprising an enclosed oil reservoir mounted to swing about a substantially vertical axis in accordance with the direction of the wind, and means for preventing

the accumulation of moisture in said reservoir comprising an air outlet passage carried by said swinging reservoir and having its orifice facing toward the lee side of the reservoir, said outlet passage including a Venturi formation.

4. A windmill construction comprising an enclosed oil reservoir mounted to swing about a substantially vertical axis, in accordance with the direction of the wind, and means for preventing the accumulation of moisture in said reservoir comprising an air outlet passage carried by said swinging reservoir and leading from the upper part thereof and having its orifice facing toward the lee side of the reservoir.

5. A windmill construction comprising an enclosed oil reservoir mounted to swing about a substantially vertical axis in accordance with the direction of the wind, means for preventing the accumulation of moisture in said reservoir comprising an air outlet passage carried by said swinging reservoir and leading from the upper part thereof and having its orifice facing toward the lee side of the reservoir, and an air inlet passage opening into said reservoir below the outlet passage.

6. A windmill construction comprising an enclosed oil reservoir having side walls and a top wall above the oil level, means for preventing the accumulation of moisture within said reservoir comprising means for collecting the moisture condensed on said side walls and conducting it to the outside of the reservoir, and heat-insulating means for the top wall to prevent moisture condensing thereon.

7. A windmill construction comprising a single enclosed chamber providing an oil reservoir in its lower part mounted to swing about a substantially vertical axis and having upwardly-extending walls above the oil level, a vertically reciprocating cross head for the pump rod operating in the upper portion of said chamber, transmission from the main shaft of the windmill to the cross head comprising a member extending into the oil in the reservoir, and means for preventing the accumulation of moisture in the oil in said reservoir comprising means for collecting the moisture condensed on said upwardly-extending walls and conducting it to the outside of the reservoir, said chamber having a substantially horizontal flat wall enclosing the upper part of the chamber, and heat-insulating means for said horizontal wall to prevent moisture condensing thereon, thus confining the condensation to the upwardly-extending walls.

8. A windmill construction comprising an enclosed oil reservoir mounted to swing about a substantially vertical axis in accordance with the direction of the wind, and means for preventing the accumulation of moisture in said reservoir comprising an air outlet passage carried by said swinging reservoir and extending outwardly therefrom and having its orifice facing toward the lee side of the reservoir.

9. In a device of the class described, a speed reducing mechanism, a casing therefor having an opening at its lower part for the circulation of air, an operative connection from which power may be obtained operating through said opening, and a ventilator mechanism located at the upper part of the casing to permit free flow of air, and cooperating with the first named opening to substantially displace the air in the casing due to atmospheric changes.

10. In a device of the class described, a casing having an opening providing access to the air

5

10

25

30

35

40

45

50

55

60

65

70

75

5 near its bottom part, a mechanism in the casing for translating rotary motion into reciprocating motion, a rod reciprocating through said opening and operatively connected to said mechanism, and a breather aperture in the upper part of the casing whereby free flow of air through the casing can take place between the breather aperture and said opening, and moisture accumulation is prevented.

10 11. In a device of the character described having an enclosure for the working parts thereof, the lower portion of said enclosure constituting a lubricant container whereby the working parts of the device will be lubricated, the upper portion of said enclosure surrounding a body of air, said casing having an opening in its lower part, an operative connection for power passing through said opening whereby air may obtain ingress and egress to the casing through said opening, and around said operative connection, and a breather passage near the top of the casing cooperating with said opening to provide free flow of air to prevent accumulation of moisture.

15 12. A windmill having an enclosure for the working parts, the upper portion of said enclosure functioning to protect the working parts of the windmill from the elements, the lower portion of said enclosure constituting a lubricant reservoir for the lubrication of the working parts 20 of the windmill, said enclosure having an open-

ing at the lower portion thereof, a power connection passing through said opening yet permitting ingress and egress of air through the opening, the upper portion of said enclosure having a breathing passageway therethrough near the top cooperating with said opening to provide free flow of air to prevent accumulation of moisture.

13. A device of the character described having a driven shaft and a reciprocating rod and mechanism for translating the rotary motion of said driven shaft into rectilinear reciprocatory motion of the rod, a casing partially enclosing said mechanism and adapted to retain lubricant, said casing being provided with an opening in its lower part through which the rod can reciprocate, which opening will permit ingress and egress of air to the casing, a rotatable tubular stem loosely surrounding a portion of said rod and supporting said casing, said tubular stem terminating above the level of the lubricant in the casing, in combination with a breather passageway in the upper part of the casing, cooperating with the opening to prevent moisture accumulation in the casing by providing free flow of air.
